UNITED STATES PATENT OFFICE.

JAMES J. KANE, OF BROOKLYN, NEW YORK.

SHIP'S-TABLE RACK.

1,246,606.

Specification of Letters Patent. Patented Nov. 13, 1917.

Application filed January 5, 1917. Serial No. 140,731.

To all whom it may concern:

Be it known that I, JAMES J. KANE, a citizen of the United States, and a resident of the city of New York, borough of Brooklyn, in the county of Kings and State of New York, have invented a new and Improved Ship's-Table Rack, of which the following is a full, clear, and exact description.

This invention relates to tables for ships and has for an object the provision of an improved construction for preventing dishes on the table from shifting to any considerable extent when the ship is being tossed.

Another object in view is to provide a table with adjustable side guards and a plurality of division members whereby the various persons using the table may retain their dishes in their immediate vicinity.

A still further object in view is the provision of a guard for the edge of the table which may be raised or lowered and positively held in the raised position when so adjusted notwithstanding the tossing of the ship.

25 In the accompanying drawing:—

Figure 1 is a perspective view of a table disclosing an embodiment of the invention.

Fig. 2 is an enlarged detail perspective view showing part of the table with certain parts broken away for better illustrating the construction of the guards.

Fig. 3 is a section through Fig. 5 on line 3—3.

Fig. 4 is a section through Fig. 5 on line 25 4—4.

Fig. 5 is an enlarged plan view of one of the guard supporting plates.

Fig. 6 is a detail fragmentary sectional view through Fig. 4 on line 6—6.

40 Fig. 7 is a plan view of the inner face of the guard adjacent the retaining plates shown in Fig. 6.

Fig. 8 is an enlarged plan view of one of the guard supporting plates for a circular 45 table.

In providing tables for ships which may encounter rough weather, it is customary to fasten the tables to the deck and also the seats. Sometimes a slight railing is provided on the table, but in calm weather this is slightly objectionable. In order to overcome this objection and yet provide means which will prevent the dishes on the table from being thrown therefrom by the pitching of the ship, a special guard has been produced which, when in use, may be raised

to the desired height and when not in use may be pushed downwardly to a position out of the way.

Referring to the accompanying drawing 60 it will be seen that the table 1 is a hexagon-shaped table supported by a suitable supporting member 2, and that a plurality of guards 3 are provided, there being one guard for each flat face of the edge of the table. 65 It is of course understood that in case the table should be of some other shape and have more or less sides there would be provided a corresponding number of guards 3. In case the table is round a single round guard 70 is usually provided and is held in place by a structure hereinafter fully described.

Co-acting with the guards 3 are a plurality of independent partitioning bars 4 which may be placed in position at any 75 time or may be folded up and stored beneath the table or at any other desired point. As shown in Fig. 2, the table 1 is provided with countersunk plates 5 and 6 each of these plates being provided with a 80 slot 7 extending vertically and having a substantially half-circular curved upper end 8. Each of the guards 3 is provided with a pair of buttons 9 formed with rounded heads 10, said buttons extending through 85 the slots 7 and held therein by their heads 10. Each of the buttons is connected with the guard 3 by a metal strip 11 countersunk into the guard, as shown in Fig. 3.

During ordinary weather the guard 3 is 90 arranged as shown in Fig. 3, but when the weather begins to be rough and the ship tosses somewhat, the guard may be raised as shown in Figs. 1, 2 and 4. As the guards are raised the same move upwardly and are 95 guided over toward the end of the curved portion 8 during their movement. It will be noted from Fig. 5 that the end of the curved portion 8 forms a pocket 12 whereby any longitudinal movement of the guard 3 100 cannot cause the removal of the head 10 from the slot 7.

In order to positively prevent any up and down movement after the parts are adjusted as shown in Figs. 2, 4 and 5, a plate 13 is provided having an elongated slot 14, said plate being secured to the guard 3 whereby the button or knob 15 may be snapped therein when moved to the proper position. Button 15 is pressed by a spring 110 16, said spring and part of said button being in the casing 17 secured in a suitable

aperture in the table 1 by any means, as for instance, by friction. A countersunk portion 18 is provided so that when the knob 15 is pushed to the rear a space will be provided 5 for the guiding or retaining pin 19. Only one button 15 has been shown but it will be evident that a greater number may be used if desired without departing from the spirit of the invention.

10 When the table is round a rounded guard is provided and supplied with a retaining button or pin 9 similar to that shown in Fig. 4, said button or pin co-acting with the diagonally arranged slot 20 in plate 21 (Fig. 15 8), said slot merging into a socket 22.

What I claim is:

1. In a guard for ships' tables, a guarding plate designed to be moved up and down, a pin extending from said guarding plate having an 20 enlargement on the outer end, a retaining plate secured to the table formed with a slot

through which said pin projects, said enlargement preventing a reverse movement of the pin, a spring-pressed button mounted on said table and projecting therefrom, and a slotted plate secured to the guarding plate 25 adapted to receive the spring-pressed button when the guarding plate is moved to a raised or operative position.

2. A guard for a ship's table, comprising 30 a plurality of guard sections arranged around a table, means for adjustably holding the guard sections in position, and a plurality of division members arranged on said table, said division members having 35 mating ends at the center of the table and a pair of shoulders near the outer end, said shoulders resting against adjacent sections while the center part of the outer end extends between said sections.

JAMES J. KANE.
